UNITED STATES PATENT OFFICE.

ROLLAND G. WILLIAMS, OF BRIDGEPORT, CONNECTICUT.

POLE MOUNTING.

Application filed January 5, 1922. Serial No. 527,179.

To all whom it may concern:

Be it known that I, ROLLAND G. WILLIAMS, a citizen of the United States, residing at the city of Bridgeport, in the county of 5 Fairfield and State of Connecticut, have invented certain new and useful Improvements in Pole Mountings; and I do declare the following to be a full, clear, and exact 10 description of the invention, such as will enable others skilled in the art to which it appertains to make and use the same.

This invention relates to certain new and useful improvements in pole mountings and pertains more particularly to an improved 15 means for holding the lower end of the pole spaced above the concrete base.

The primary object of the invention is to provide means for holding the pole which avoids the boring of a hole through the 20 pole to receive the bolt, as shown in my Patent No. 1,392,730 dated October 4, 1921.

A further object of the invention, is to provide supporting means which not only avoid boring of the pole, but which also 25 hold the pole against turning and which further grip the pole for a material distance along two spaced lines on each of the diametrically opposed sides thereof.

The invention further aims to provide a 30 pole mounting which is of simple and economical construction, positive in action and capable of being easily and quickly applied.

In the drawings:—

Figure 1 is a side elevation, and

Figure 2 is a section on line 2—2 of Figure 1.

In proceeding in accordance with the present invention, a concrete base B is employed to which a pair of opposed spaced 40 base supports 14 of L-shape are suitably secured by means of bolts, the same being adjustable by virtue of the pair of slots 3 in one of the supports through which slots 45 the bolts pass.

A pair of elongated plates 4 are provided each having their sides extending inwardly and tapered to form tongues 8 which bite into the opposite sides of the pole A as will 50 now be described. Tie plates 5 are engaged with the vertical webs 6 of the base supports or sections 1 and are also engaged with the backs of the plates 4, the plates 4 and 5 seating at their lower ends on the 55 concrete base. Bolts 7 of curved form are

engaged with the parts of the pole occurring between the plates 4 and are arranged beyond but adjacent to the tongues 8, so that in assemblage, the bolt ends will act to prevent lateral movement of the plates 60 4. The ends of the bolts are passed through apertures provided therefor in the tie plates 5 and are equipped with nuts 9 and 10.

In assembly, the plates 4 and 5 are seated at their lower ends on the concrete base 1, 65 the pole being held in any suitable manner with its lower end spaced above the upper face of the concrete base, to thereby leave free space between the lower end of the pole and the upper face of the concrete base 70 so that water can freely flow therebeneath and air can gain access to the pole bottom face to maintain same dry thereby preventing rotting. The bolts are applied in the position shown in the drawings and the 75 nuts thereof tightened to thereby draw the plates 4 towards each other and to cause the tongues 8 thereof to bite into the pole, the depth of the bite being controlled by the degree of tightening of the nuts. The 80 pole is thus supported at four distinct points or lines, the latter of considerable length so as to afford a firm and substantial support for the pole, so that the pole is not only held spaced above the concrete base, 85 but is further held against turning, without the necessity of boring a hole through the pole. The pole is thus not weakened by the boring of a hole therethrough, but is also firmly supported for a considerable 90 distance at each of four points equidistantly spaced, or at points of about 90° apart. As depicted in the drawings, the lowermost bolts pass through the vertical webs 6 of the base supports thereby holding the plates 4 against lateral movement, 95 like movement of the plates 5 being prevented by the bolts which engage the outer sides of the tongues 8.

What is claimed is:

1. In a pole mounting, a base, a pair of approximately L-shaped supports, means to secure the supports to the base, a pair of opposed plates having inwardly extended tongues along the sides thereof formed to 105 bite into pole, a pair of perforated tie plates engaged with the backs of the respective first named plates, and series of opposed curved bolts having nuts thereon, the bolt ends being passed through the perforations 110

100

of the tie plates, parts of the bolts being engaged with the parts of the pole between the tie plates and arranged to lie adjacent to the outer sides of the tongues so as to 5 confine the first named plates between the opposed bolts, the lower bolts being extended through the vertical webs of the base supports and all of the plates seating on the base and holding the lower end of the 10 pole spaced above the base.

2. In a pole mounting, a base, supports thereon, a pair of opposed plates having projecting side tongues formed to bite into the opposite sides of a pole, perforated tie 15 plates engaged with the backs of the first named plates, and opposed series of bolts passed through the perforations of the tie plates and receiving the first named plates therebetween, all of the plates seating on 20 the base to hold the pole spaced thereabove

and the lower bolts being connected to the base supports.

3. In a pole mounting, a base, supports thereon, opposed members seated on the base and arranged between the supports and having means to bite into the pole to hold the lower end of the latter spaced above the base, perforated tie elements engaged with said members, and means to secure the elements together. 25

4. In a pole mounting, a base, supports thereon, opposed pole holding members seated at their lower ends on the base and engaged with said supports and having means to bite into the pole to hold the latter 30 spaced above the upper face of the base, and means to secure the members to the pole. 35

In testimony whereof I affix my signature hereto.

ROLLAND G. WILLIAMS.
